UNITED STATES PATENT OFFICE.

JOSEPH P. FOX, OF ST. CLOUD, MINNESOTA.

SIGN.

Application filed December 27, 1921. Serial No. 524,979.

To all whom it may concern:

Be it known that I, JOSEPH P. Fox, a citizen of the United States, and a resident of St. Cloud, in the county of Stearns and State 5 of Minnesota, have invented certain new and useful Improvements in Signs, of which the following is a specification.

This invention relates to a sign particularly adapted for gasolene retail stations or 10 the like.

The object of the invention is to provide an artistic and attractive sign which may be easily positioned in a conspicuous manner at a retail gasolene station, or the like, and 15 which is adapted to carry numerals for indicating the retail price of gasolene or other commodity.

It is also an object of the invention that the sign in itself be of sufficient size so that 20 the name or abbreviation thereof indicating the commodity being sold may be printed upon the sign so that it may be easily read.

A further object of the invention is that the sign be adapted to indicate the price 25 of the commodity sold not only in cents but in fractions thereof.

Other objects will hereinafter appear.

The invention is illustrated by way of example in the accompanying drawings, in 30 which:

Figure 1 is a front elevation of a sign embodying the present invention.

Figure 2 is a sectional view taken substantially on the lines 2—2 of Figure 1.

Figure 3 is a vertical sectional view taken substantially on the lines 3—3 of Figure 1.

Figure 4 is a detail perspective view of one of the number bearing plates.

Referring to the drawings more particularly, 10 indicates generally a plate which is circular in shape and having its edge turned upon a wire 11 to form a bead 12. The plate 10 is preferably made of sheet metal and may be painted any color desired.

45 The plate 10 is horizontally recessed as at 13, said recess being rectangular in shape, and upon the forward face of the plate there is mounted a flap door generally indicated by the reference character F, said flap door 50 being adapted to cover the recess 13 and consisting in a metallic sheeting rectangular in cross section and having its upper edge turned forwardly upon a rod 14 and forming the bead 15. The ends of the rod 14 55 are journaled by the clips 16 which are soldered or otherwise secured to the plate 10.

Also directly above the upper edge of the flap door F there is secured a strip 17 which is formed with a downwardly depending curved lip 18 adapted to fit upon the bead 60 14 for the purpose of preventing water entering beneath the upper edge of the flap door F.

One end of the door has its edge turned inwardly and upon its forward face as at 65 19, Figures 1 and 2, and its lower edge is also turned in a similar manner as at 20, Figures 1 and 3. The inturned edge portions are spaced with relation to the front face of the flap door and adapted to serve 70 as guide means for number bearing plates 21. Also there is secured upon the front face of the plate a pair of guide members 22, said guide members each consisting in a body portion having each of its longitudinal 75 edges bifurcated to provide a pair of furcations 23 along each edge thereof which are adapted for receiving the edges of the number bearing plates 21. The number bearing plates 21 are of a large size and two in 80 number and are for indicating the price in cents for a gallon of gasolene. Each number bearing plate is formed with a lip 24 along its upper edge which is adapted to slip beneath the hinge 15 of the flap door F for 85 holding the number bearing plates in position.

Also I provide means for indicating a fraction of a cent should this be necessary to show the correct price of the gasolene. 90 In accomplishing this I provide the plates 25, the inner ends of which are adapted to extend in between the furcations 23 of the associated guide member 22. Also between the plates there is positioned another guide 95 member generally indicated by the reference numeral 26 which is bifurcated along its edges similar to the guide members 22 and adapted for receiving the edges of number bearing plates 25. The lower edge of the 100 lowermost plate 25 slides between the front face of the flap door F and its turned in edge 20, while the upper edge of the uppermost plate member 25 slides within a guide member generally indicated by the reference 105 numeral 27. The number bearing plates 25 are each formed with a lip 25', the same as the number bearing plates 21. Also adjacent each end of the flap door F I provide a bead strip 28 which is to seal the space 110 between the flap door and plate 10 at the ends thereof.

It is of course apparent when using a sign of this character that it would be desirable to have different numbers for indicating the change in price of the commodity being sold, and it would also be convenient if these numbers were carried by the sign itself and thereby obviating any possibility of loosing the same. For this purpose I provide a pocket generally indicated by the reference character P, which consists in a bottom 29 and the side and end walls 30. Entirely about the upper edge of the side and end walls there extends a lip 31 which affords a means by which the pocket may be soldered or otherwise suitably secured to the pocket 10. The pocket is shown upon the rear face of the plate 10 and directly beneath the flap door F. Any number of the bearing plates 21 and also plates 25 may be disposed in the pocket P and retained for future use.

It is preferable that the flap door F should be at all times held closed, and for this purpose I provide a pair of coiled springs 32, Figure 3, each of which has its one end connected to the flap door and its other end secured to the plate 10 and adapted to normally resist the opening of the flap door.

In the use of the present device, the name of the commodity to be sold may be printed upon the plate 10 preferably above the flap door F. Also there may be printed the word "today" to indicate the time at which the price therebeneath prevails. Any arrangement of this kind may be made which would be most attractive. The number bearing plates are then arranged upon the flap door F to indicate the price.

It may be mentioned that the lips 25' on the small number bearing plates 25 hold the plates in their position by their engagement with the associated bead 28.

While I have shown and described my device as being particularly adapted for use in connection with a gasolene retail station, I wish it to be understood that I am not to be so limited as I am aware of the fact that the sign may be used with equal advantages for indicating the price of other commodities.

I claim:

1. A sign of the character described, comprising a plate, a pocket formed centrally in the plate, a flap door hinged to the plate

and adapted to form a closure for said pocket, and a plurality of number bearing plates detachably supported upon the outer face of the flap door for indicating the price of a commodity.

2. A sign of the character described, comprising a plate upon which the name of a commodity may be indicated, a flap door hinged to the front face of said plate and extending there across, guide means carried upon the front face of said flap door adapted to detachably support single number bearing plates by which the price of the commodity may be indicated, and other guide means carried by the flap door whereby a pair of numbers may be detachably supported one above the other for indicating the fraction of a single member for further indicating the price of a commodity.

3. A sign of the character described, comprising a circular plate having a bead formed about the edge thereof and adapted for indicating upon the front face thereof the name of commodity, a flap door having its upper edge hinged to the plate and extending across the plate, a pocket beneath said flap door, means for sealing the flap door against the entrance of water to the pocket, and guide means carried upon the front face of said flap door adapted for detachably supporting number bearing plates by which the price of a commodity may be indicated.

4. A sign of the character described, comprising a circular plate, a flap door hinged upon the front face thereof, a pocket beneath said flap door adapted to receive a plurality of number bearing plates, means by which said flap door will be normally and yieldingly held against outward swinging movement, and guide means carried upon the front face of said flap door adapted for detachably supporting number bearing plates for indicating the price of a commodity.

5. A sign of the character described, comprising a plate formed with a pocket, a door hinged to the plate and adapted to form a closure for said pocket, a plurality of plates adapted to be detachably positioned upon said door for indicating the price of a commodity, and means for yieldably holding the door in its closed position.

JOSEPH P. FOX.
